UNITED STATES PATENT OFFICE.

SOLOMON GLOOR, OF BURLINGTON, IOWA, ASSIGNOR TO CHARLES F. EBNER, OF SAME PLACE.

GUN-CLEANER.

SPECIFICATION forming part of Letters Patent No. 593,648, dated November 16, 1897.

Application filed April 10, 1897. Serial No. 631,490. (No model.)

To all whom it may concern:

Be it known that I, SOLOMON GLOOR, a citizen of the United States, residing at Burlington, in the county of Des Moines and State of Iowa, have invented certain new and useful Improvements in Gun-Cleaners; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to those gun-cleaners composed of a pivoted scraper attached to a stem adapted to be screwed on the end of a jointed or other cleaning-rod.

20 The purpose of my device is to provide a cleaner wherein the pivoted scrapers are reversible, so that they will operate on the inside of the barrel during the backward and forward reciprocations of the cleaning-rod, and to pivot these scrapers in such a manner 25 upon a stem having attaching devices at its opposite ends, whereby either end can be attached to a cleaning-rod when necessary.

With this object in view my invention consists in the peculiar features and combinations of parts more fully described hereinafter and pointed out in the claims.

30 In the accompanying drawings, Figure 1 represents a perspective view of my device attached to a section of a cleaning-rod; Fig. 35 2, a horizontal view showing the scraper in longitudinal section, and Fig. 3 an end view.

The reference-letter A denotes the stem, to which the pivoted scrapers are attached. This stem is by preference composed of a round 40 bar of metal having its opposite ends provided with screw-threads b, which terminate at shoulders c. Both ends of the stem are constructed exactly alike, so that either can be attached to the end of a cleaning-rod i 45 with equal facility. This stem is made long enough to allow the threaded ends to project a slight distance beyond the ends of the scrapers d. These scrapers consist of a pair

of elongated concaved plates of sheet spring metal, preferably brass. Their opposite ends 50 flare outwardly, so that when the parts are assembled the scrapers are substantially bell-shaped at both ends and are beveled at e to form a sharp edge, which is adapted to have spring-pressure and scrape against the inside 55 of the gun-barrel. Both scrapers are pivoted at the middle on a transverse stud or pin f, which passes through a pair of overlapping lugs g on the sides of the scrapers. The flaring ends h of the scrapers are wider than their 60 body portions, in order to engage a larger area of the surface of the inside of the gun-barrel.

Thus constructed it will be observed that either end of the cleaner can be screwed upon 65 the end of a cleaning-rod with equal facility and that in case the device should stick within the barrel and it should be desirable to unscrew the rod for the purpose of attaching and pulling the cleaner from the other end of the 70 gun-barrel it can be readily done, and often much annoyance and labor saved thereby.

Another advantage of my device is that it can be used with equal facility in a ten or twelve gage gun.

Having thus described my invention, what I claim as new, and desire to secure by Letters Patent, is—

1. In a gun-cleaner, a central stem, in combination with a pair of concaved elongated 80 spring-plates pivoted to the middle of the rod so as to rock loosely and having outwardly-flaring ends, substantially as described.

2. In a gun-cleaner, the combination with a central stem having screws at both ends, of 85 a pair of elongated spring-plates provided with widened flaring ends, and centrally pivoted to loosely rock on the stem substantially as described.

In witness whereof I affix my signature in 90 presence of two witnesses.

SOLOMON GLOOR.
